UNITED STATES PATENT OFFICE.

WILLIAM B. FORD, OF DECATUR, ILLINOIS.

RIGHT AND LEFT BASIN-COCK.

SPECIFICATION forming part of Letters Patent No. 658,252, dated September 18, 1900.

Application filed July 5, 1898. Renewed August 13, 1900. Serial No. 26,710. (No model.)

To all whom it may concern:

Be it known that I, WILLIAM B. FORD, of Decatur, in the county of Macon and State of Illinois, have invented a certain new and useful 5 Right and Left Basin-Cock, of which the following is a specification.

This invention is designed to provide a basin-cock that may be used either as a right-hand cock or a left-hand cock. It is exemplified in the structure hereinafter described, 10 it is defined in the appended claims, and its advantages are obvious to persons skilled in the art to which it relates.

In the drawings forming part of this specification, Figure 1 is a plan of a cock embodying my invention. Fig. 2 is an elevation of the cock. Fig. 3 is a central vertical section through the novel portion of the device. Fig. 4 is an elevation of a modified form of the cock. 20 Fig. 5 is a vertical section through a fragment of the modified form.

In constructing a cock in accordance with my idea a vertical body is made in any desirable manner except for the peculiarities 25 hereinafter described, and it is provided with a suitable valve and valve-stem. On the upper end of the valve-body a nozzle is mounted in communication with the bore of the body and in a manner to permit horizontal swing, 30 and an adjustable bearing is connected with the body in position to grip the nozzle and hold it in any desired position with relation to the valve-stem.

The details of construction may be as follows, namely: The upper portion of the body 35 1 is reduced to form the stem 2. The stem is exteriorly threaded, as shown at 3, and it is bored lengthwise and laterally to permit passage of water. The nozzle 10 fits over the 40 smooth portion of the stem 2, with its lower surface resting against the shoulder formed by the reduction of the body, and a nut 6 is screwed onto the threaded portion of the stem and into contact with the upper surface of 45 the nozzle with a sufficient firmness to hold the nozzle from turning on the stem and prevent leakage. Whenever it is desired to turn the nozzle to change the character of the cock, the nut is first loosened and then retightened 50 after the nozzle is shifted to the desired position. To provide for close joints between the body and nut and the nozzle, the shoulder of

the body is preferably recessed, as shown at 4, the nut is recessed, as shown at 7, gasket-washers 5 and 8 are placed in the recesses, 55 and annular bearing-surfaces 11 on the portion of the nozzle-encircling stem 2 are made to bear against the washers. It is obvious, however, that a mechanic may easily construct a practical modification of this particular joint, and I do not confine myself in this regard further than the claims indicate. The lateral bore in the stem is diametrical, and so the nozzle will readily take water from either side of the stem; but to obviate the necessity 60 of accurate adjustment of the nozzle and to increase the availability of the cock the portion 9 of the nozzle encircling the stem is preferably enlarged to form a water-passage, and when this is done the cock will be operative 70 with the nozzle projecting in any direction from the stem.

The invention is shown in a modified form in Figs. 4 and 5, where the nozzle is clamped between two parts of the body of the cock, 75 the upper part acting as the mechanical equivalent of the nut 6. In this case a hollow threaded stem 1^b is extended upward from the lower portion 1^a of the body, the annular portion 9^a of the nozzle is fitted around the 80 stem, and the upper portion of the body is screwed onto the stem and against the nozzle. The stem 1^b is virtually the same as stem 2, the nozzle 10^a is the same as 10, and the part 1 of the body acts on the stem and on the nozzle precisely the same as does nut 6. 85

What I claim is—

1. In a right and left basin-cock, a body comprising parts adjustable lengthwise with relation to each other, such parts being conjoined by means of a reduced hollow cylinder forming part of the body, and a nozzle swingable on the cylinder in communication with the interior thereof, whereby the nozzle may be swung to any desired position and clamped 95 there, substantially as set forth.

2. In a right and left basin-cock, a hollow cylindrical stem reduced with relation to the body and forming part thereof a nozzle encircling the stem and communicating with the interior thereof, and an adjustable bearing on the stem adapted to be forced against the nozzle, substantially as set forth. 100

3. In a basin-cock, a hollow exteriorly-

threaded stem on the body of the cock communicating with the body and having an outlet-opening, a nozzle encircling the stem, and a nut on the stem adapted to bear against the nozzle.

4. In a basin-cock, the body 1, the reduced stem 2 bored and threaded, the recess 4 in the shoulder of the stem, the gasket 5 in recess 4, the nozzle 10 encircling the stem and hav-

ing the annular bearings 11, the nut 6 having 10 the recess 7, and the gasket 8 in recess 7, substantially as described.

In testimony whereof I sign my name in the presence of two subscribing witnesses.

W. B. FORD.
